BASE FOR A PENHOLDER

Warren Shea, Jersey City, N.J., assignor to Rotary Pen Corp., Kenilworth, N.J., a corporation of New Jersey

Application March 24, 1959, Serial No. 55,144

Term of patent 14 years

(Cl. D74—1)

FIG.1

FIG.2

FIG.3

Fig. 1 is a top perspective view of a base for a penholder showing my new design;

Fig. 2 is a top plan view; and

Fig. 3 is a side elevational view thereof looking in the direction of the arrows 3—3 of Fig. 2.

I claim:

The ornamental design for base for a penholder, substantially as shown.
